Des. 209,396
Patented Nov. 28, 1967

209,396

ULTRASONIC PLASTICS WELDER

Thomas J. Scarpa, Metuchen, N.J., assignor to Edison Instruments, Inc., Rahway, N.J., a corporation of New Jersey

Filed Jan. 3, 1966, Ser. No. 425

Term of patent 14 years

(Cl. D26—1)

The single view of the drawing shows in perspective from the front of my new design for an ultrasonic plastics welder. The rear is substantially plain; the side opposite the side shown is substantially plain, except as indicated.

What I claim is:

The ornamental design for an ultrasonic plastics welder, substantially as shown and described.
